W. S. MOORE.

Lard Lamp.

No. 2,950.

Patented Feb. 10, 1843.

UNITED STATES PATENT OFFICE.

WM. S. MOORE, OF SPRINGFIELD, ILLINOIS.

LARD-LAMP.

Specification of Letters Patent No. 2,950, dated February 10, 1843.

To all whom it may concern:

Be it known that I, WILLIAM S. MOORE, of Springfield, in the county of Sangamon and State of Illinois, have invented a new and useful Improvement in Lamps for Burning Lard, which is described as follows, reference being had to the annexed drawings of the same, making part of this specification.

10 Figure 1 is a vertical section.

This improvement consists in constructing the lamp with a spiral thread or male screw A on the circumference of the top of the lamp stand B, corresponding with a 15 spiral groove or female screw C formed on the inside of the lamp or lard holder D for the purpose of depressing the wicks as the lard is consumed, or in other words bringing the burners nearer to the surface of the 20 melted lard as the consumption goes on, by simply turning the lard holder D to the right while the stand B remains permanent, the wick tubes E descending into the cavity F in the center of the stand B. By this operation the lard is kept always in contact

with the flame by a gradual and easy movement of the screw. There are other improvements in the lamp but this is the most essential.

The stand B may be constructed in the usual manner except the head of the same upon which the lard rests and on which the male screw around the circumference of the same is formed. The lard holder D may also be constructed as is usual with the exception of the addition of the female screw on the inside thereof. The wick tubes E and basin G are likewise made in the usual manner.

What I claim as my invention and which I desire to secure by Letters Patent is—

Constructing the lard lamp with a male screw on the circumference of the head of the stand and a corresponding female screw on the inside of the lard holder in the manner and for the purpose herein set forth.

W. S. MOORE.
